UNITED STATES PATENT OFFICE.

JACOB SCHICK, OF WEST ORANGE, NEW JERSEY, ASSIGNOR TO MAGAZINE REPEATING RAZOR COMPANY, A CORPORATION OF NEW JERSEY.

RAZOR.

Application filed October 10, 1924. Serial No. 742,759.

This invention relates to an improved razor of the safety type which is compact and well balanced and which is so constructed as to permit the ejection of a blade and the insertion of another by means of a manually operated device so that the blades can be inserted without their being handled separately, as they are fed in succession from a stack.

10 The invention comprises a razor that is constructed so that the blades are fed end-wise from the stack into the guard and the blade that is being inserted expels the blade in the guard.

15 The invention also relates to a razor of the safety type which has a handle and a guard connected together so that when the guard is swung to extend longitudinally from the handle it is in position to receive a 20 blade from the stack, the handle acting when desired, as a receptacle or holder for the stack, and the guard when supplied with a blade being swung to shaving position on the handle.

25 The invention is also designed to provide a compact razor in which the handle as a reservoir for the blades, the guard, and the means for feeding the blades from the stack to the guard are placed within a structure 30 the size of the usual safety razor and in which the blade may be held when in use at an angle relative to the handle.

The invention also relates to a holder for 5 a stack of blades which is detachable from the handle for reloading and which co-operates with a slide on the handle for successively feeding the blades from the stack.

Another object of the invention resides in providing a blade supporting head comprising a solid block provided with a slit of approximately the dimensions necessary to receive and retain a blade; the block on one side of the slit being formed or provided with a curved safety guard and the entire block being designed to bring the slit into registry with the feeding opening from the handle or magazine for reserve blades.

Another object of the invention is to provide a clamp for locking the blade in the guard which clamp is operated when the guard is swung to shaving position but which is eased off enough to allow smooth passage of the blade when the guard is moved to the position in which it receives a blade. The swinging of the guard is about

a cam projection on a supporting post which, in addition to serving the purpose of clamping the blade in the guard when the guard is swung to a shaving position also has the purpose of coacting with the clamp 60 or spring to hold the head of the razor at any desired angle with the handle to suit the individual user.

The adjustment is designed to permit a firm positioning of the shaving edge at a 65 variety of angles in relation to the longitudinal axis of the handle without independent manipulation of any clamping means.

The invention also provides a structure which prevents the entrance of water to the 70 stack of blades or other elements within the handle.

The invention further embodies a clip in which the stack of blades is held and which 75 clip carries the stack bodily into the handle and is installed so as to permit the feeding means to move the blades successively from the stack and which is also expendable in that it can be thrown away, it being the intention to sell blades in the clip ready for 80 insertion in the razor.

The invention is illustrated in the accompanying drawing in which Figure 1 is a side view of a razor as it appears when closed and assumes the compact form in which it is 85 made. Figure 2 is a section of the razor with the guard and the post shown in elevation. Figure 3 is a fragmentary sectional view of the upper right hand part of Figure 2 but with a blade fed into the guard. Figure 4 is a side view of the construction shown in Figure 2 with the sleeve on the handle shown in section. Figure 5 is a top view of the construction shown in Figure 1 with the cover removed. Figure 6 is a section on line 6-6 in Figure 2. Figure 7 is a perspective view of the trigger for feeding the blade forward and Figure 8 is a perspective view of a form of clip for holding a stack of blades showing one blade ready 100 for insertion in the clip. Figure 9 is a detail section showing how a blade is locked in the guard when the guard is in shaving position.

The handle 10 is provided with the guard 105 11, these being secured together so that the guard can be swung to shaving position or extended longitudinally relative to the handle. The construction shown embodies a post 12 on the end of the handle which re- 110

ceives the slot 13 of the guard and the screw 14 acts as a pivot and permits adjustment so that the swinging movement is not too free and to shift the guard it is necessary to 5 positively grasp and turn it.

The guard has the curved front edge 15, usually toothed to permit easier shaving, the front edge being faced as at 16 to bear against the face of the user so as to gauge 10 the pressure on the face. The guard has a slit 17 usually inclined at a good shaving angle and receives and holds a blade 18 which fits snugly in the slit 17. The blade 18 is inserted endwise into the slit and I 15 provide means for receiving and holding the blade with an easy friction by means of a spring 19 which projects up through an opening in the bottom of the slot 13 and bears on the blade.

20 When the guard is swung away from its longitudinal position or to horizontal position, which is the shaving position (illustrated in dotted outline in Figure 2) the blade is tightly clamped as the spring is 25 pressed upward by the end 20 of the post 12, which end is raised or made eccentric to the pivot 14 and acts as a cam to bind the blade in place. Of course, the spring 19 can be dispensed with but I prefer to use it to prevent 30 the blade sliding in the slit when the guard is folded or swung against the post.

This clamping, of course, also holds the guard in its adjusted positions for shaving as most convenient for the user.

35 The blades are preferably carried in the handle, and for this purpose I provide the handle with a recess which receives the stack of blades and also parts associated with the handle to insure the blades being in position to be fed into the guard. In the form shown the holder 22 is an open-sided frame having a spring 23 secured thereto so as to bear on the underside of the stack. The holder 22 is on a stem 24 which is rectangular 40 so that it fits in the recess 21 and cannot turn and the head 25 which screws on the end of the handle is swivelled on the stem 24. In the drawing this is shown as a disc 26 fitting in a recess 27 in the head 25. This 45 swivelling is also desirable as the stem 24 and the holder are eccentrically placed in the handle as will be seen from Figures 2, 4 and 6 and for reasons to be stated hereinafter.

50 To feed a blade from the stack to the guard I provide a slide which in the form shown comprises a sleeve 28 with a firm sliding fit on the handle and which carries a trigger or finger 29 which has a rounded 55 outer face 30 bearing against the inside of the sleeve to which it is secured, as by a screw 31. The finger or trigger 29 is set in on the outer face of the handle, the faces 32 sliding on the faces 33 of the flattened part 60 of the handle flanking the slot 34 through

which the finger slides. The projection 35 is just inside the slot and is so proportioned that when the slide is pulled back it catches just under the outermost or what might be termed the topmost blade of the stack as in 70 Figure 2.

The projection 35 is of slightly less thickness than a blade so that it only picks one up and slides it forward when the sleeve 28 is pushed forward. The blade passes 75 through the slit 36 and into the slit 17 of the guard, the sleeve being halted when the blade is positioned, as the trigger 29 engages the end 37 of the slot 34 and the projection 35 is long enough to reach the end of the 80 slit 36 which is also the edge of the guard as the parts are so proportioned that the guard rests against the top face of the handle when the guard is in extension or arranged longitudinally on the handle. The 85 return of the sleeve and the trigger does not disturb the stack as the next succeeding blade is still under the trigger as shown at 38 in Figure 3.

To prevent water entering the handle I 90 provide a flap 39 which normally is held shut by a light spring 40 and is only displaced when a blade passes through the slit 36.

While the blades can be directly stacked 95 in the holder, I intend to supply them already stacked in a clip 41 which has a side wall 42 and end walls 43 and an open bottom 44 through which the spring 23 can project. The flanges 44 hold the blades 100 from dropping through the bottom and the very short flanges 45 just engage the very corners of the sharpened edges of the blades so that the blade is fed through without any injury to the cutting edge except possibly at 105 the tip on each end. The clips 41 are wrapped and form the package of blades as sold to the user and when the wrapper is removed the clip can be inserted between the ends 46 and 47 of the holder 22 into which 110 space it fits. The holder with the clip is then slid into the handle and the cap 25 screwed on. The clip cannot project to interfere with the feeding of the top blade as it is held slightly retreated by the shoulder 115 48 (see Figure 6.)

The major portion of the guard is rounded to coincide with the contour of the handle, and the handle 10 projects above the sleeve 28 enough to provide an edge 49 to 120 frictionally hold a cap 50 which is placed over the guard and forms a symmetrical and well balanced razor as will be seen from Figure 1.

As stated before, the recess for the stack 125 of blades is not centrally located in the handle. It is placed to one side of the centre so that it can be fed into the forward end of the guard. The guard is thus held with its slit 17 just above and in line with 130

the slit 36 in the handle. This places it eccentrically relative to the centre of the device as will be seen from Figure 5. To bring the guard to horizontal position with its blade inclined to the proper shaving angle, I incline the post 12 relative to the centre of the handle and to the blade carrying slits, the result being that the guard swings in a plane at an angle to the path 10 of the blade when it is fed into the guard. This disposition of the parts causes the guard when in shaving position to be so placed that the blade is inclined to the proper shaving angle as in Figure 4 instead 15 of horizontal which would be the case if the guard was to swing in a plane parallel to the feeding movement of the blade.

The amount of cant of the blade is regulated by the inclination of the post or rather 20 the pivot of the guard relative to the feeding plane of the blade.

It will be understood that modifications and changes can be made in the form and sizes of the parts without departing from 25 the scope of the invention.

I claim:

1. A razor comprising a magazine which constitutes a handle, the magazine being adapted to receive a stack of blades, a guard 30 pivoted on the end of the handle and having a slot to receive a blade endwise, and a slide on the handle having a projection to propel a blade from the stack into the guard.

2. A razor comprising a handle with a stack of blades therein, a guard for holding a blade in saving position on the handle, and a slide movable longitudinally on the handle and having a projection for moving a blade endwise from the stack to shaving position 40 in the guard.

3. A razor comprising a handle with a stack of blades therein, a guard for holding a blade in saving position on the handle, a slide movable longitudinally on the handle and having a projection for moving a blade endwise from the stack into the guard, and a friction device in the guard for holding the blade whereby a blade in the guard is ejected by the blade that is inserted.

4. A razor comprising a handle having a recess to receive a stack of blades, a guard pivoted to the handle so as to be disposed longitudinally thereon or at an angle thereto, the handle having a slit to permit the passage of a blade from the stack when the guard is longitudinal, and a slide for moving a blade from the stack into the slit.

5. A razor comprising a handle adapted to hold a stack of blades, a guard pivoted to the handle so as to be transversely arranged when in saving position, and means for feeding a blade from the stack into the guard when the guard is arranged longitudinally on the handle.

6. A razor comprising a handle with a

recess therein for receiving a stack of blades, a post on the end of the handle, a guard pivoted intermediate its ends on the post and having a slit to receive and hold a blade in shaving position, and a slide on the handle 70 for sliding a blade from the stack into the slit in the guard when the guard is swung to a position to receive the blade.

7. A razor comprising a handle with a recess therein for receiving a stack of blades, 75 a post on the end of the handle, a guard pivoted intermediate its ends on the post and having a slit to receive and hold a blade in shaving position, and a slide on the handle for sliding a blade from the stack into the 80 slit in the guard when the guard is swung to a position to receive the blade, the parts being disposed so that the plane in which the guard swings is at an angle to the path of movement of the blade.

8. A razor comprising a guard to receive a blade endwise to a shaving position, a holder for a stack of blades, and positive means on the holder for successively feeding the blades from the stack into the guard.

9. A razor comprising a guard with a slit for receiving a blade endwise and holding it in shaving position, a clip for holding a stack of blades, and positive means for sliding the blades successively from the stack 95 endwise into the slit.

10. A razor comprising a handle with a recess therein, a guard secured on the end of the handle, a clip adapted to hold a stack 100 of blades, the clip being insertible and removable into and from the recess in the handle, and a slide movable across the mouth of the clip to slide the topmost blade from the stack into the guard.

11. A razor comprising a handle having a 105 recess therein, a clip holder insertible in the recess, a clip fitting the holder and adapted to hold a stack of blades, a slide to successively move the blades endwise from the handle, and a guard mounted on the handle 110 and adapted to be alternately swung from shaving position to a position to receive a blade from the handle.

12. A razor comprising a handle, a recess in the handle, a removable holder for a stack 115 of blades in the recess, means on the handle for feeding a blade from the stack out of the handle, and a guard on the handle and pivoted so as to swing, the guard having a slit to receive a blade propelled from the handle, and means for clamping the blade in the guard said means being actuated when the guard is swung to shaving position.

13. A razor comprising a handle, a recess in the handle, a removable holder for a stack 125 of blades in the recess, means on the handle for feeding a blade from the stack out of the handle, and a guard on the handle and pivoted so as to swing, the guard having a slit to receive a blade propelled from the handle,

- and means for clamping the blade in the guard when the guard is swung to shaving position, the guard swinging in a plane that is at an angle to the path of the blade.
5. 14. In a razor, a post, having a rounded top edge, a pivotal pin eccentric to said edge, a guard pivoted on the pin, a slit to receive a blade, said slit being over said edge so that the edge clamps the blade when the 10 guard is in shaving position.
15. In a razor, a post having a rounded end, a guard arranged to swing on the post eccentrically relative to said end, the guard having a slit to receive a blade, a spring under the slit to frictionally hold a blade in place, the spring being pressed to clamp the blade when the guard is swung to shaving position.
16. A razor comprising a head having a 20 slot to hold a blade, a container, a plurality of separate blades in said container, means for advancing a blade endwise from said container into said slot whereby the blade in said slot is ejected therefrom by the blades 25 so advanced.
17. A razor comprising a head having a slot to hold a blade, a handle, a container in said handle, a plurality of blades separate in said container, and means for feeding a blade from said container into said slot and 30 the blade so fed causing the release of the blade in said slot.
18. A razor comprising a blade holding device, a handle, a blade magazine within said handle, and means for advancing a 35 blade from said magazine toward said blade-holding device.
19. A razor comprising a holder, a stack of blades in the holder, a shaving head pivoted on the holder and adapted to be swung to one position for receiving a blade and to another position for shaving, and means for expelling a blade from the stack to the shaving head when the latter is in receiving 40 position.
- 45 In testimony that I claim the foregoing, I have hereto set my hand, this 8th day of October, 1924.

JACOB SCHICK.
